Inventor

Malcolm McCormick
by August Edward Atty.

UNITED STATES PATENT OFFICE.

MALCOLM McCORMICK, OF WYANDOTTE, MICHIGAN, ASSIGNEE TO McCORD MANUFACTURING COMPANY, OF DETROIT, MICHIGAN, A CORPORATION OF NEW YORK.

MERCHANDISING CHART.

Application filed March 3, 1922. Serial No. 541,305.

To all whom it may concern:

Be it known that I, MALCOLM McCORMICK, a citizen of the United States, residing at Wyandotte, in the county of Wayne and State of Michigan, have invented new and useful Improvements in Merchandising Charts, of which the following is a specification.

This invention relates to charts for identifying the different parts made by one manufacturer for use in various devices as marketed by others, and thus aid in the merchandising of said parts.

The invention has particular reference to cylinder head and other gaskets used in connection with motors on automobiles, trucks, tractors, and other devices making use of internal combustion engines.

By means of the charts of my invention, 20 the jobber, dealer, and repair man have at hand means for readily and quickly identifying the particular gaskets used in and about the motors of the devices covered by the charts by referring to the names of the 25 devices when known, or to such other data contained in the charts about said devices, or to the motors used thereon, as an aid in identifying the gaskets used in said devices.

The invention consists further in the matter 30 ters hereinafter described and more particularly set forth in the appended claims.

In the accompanying drawings—

Figs. 1 to 4 inclusive show charts having in alphabetical arrangement the names of 35 various passenger cars, tractors, trucks, and other miscellaneous devices using internal combustion engines or motors wherein gaskets are employed; and

Figs. 5 to 9 inclusive illustrate other 40 charts for use in connection with the ones just mentioned, illustrating certain of the gaskets mentioned in the first set of charts and also containing certain data with respect to such gaskets to carry out the features of 45 my invention.

Chart 1, illustrated in Fig. 1, is headed "McCord cylinder head gaskets," thus giving the name of the manufacturer of the gaskets and the particular class or kind of 50 gaskets covered by the chart. Beneath this heading is the designation "Passenger cars," thus indicating the particular class of motor vehicles covered by chart 1. Below this certain information or data appears on the 55 chart and this is divided or arranged in six

vertical columns. The first column, 2, is headed by the name of the gasket manufacturer, as "McCord," and under this is a symbol or abbreviation "No." for the word "number." Then follows a list of numbers 60 adopted by the gasket manufacturer to indicate the various cylinder head gaskets made by him for the passenger cars listed in the next column 3. Should any of the passenger cars listed in column 3 employ a motor with 65 a solid head, no cylinder head gasket would be used, and that fact would appear in column 2 by the abbreviation "SH" as at 2^a, in lieu of a number.

Column 3 is headed by the word "Car" 70 and under that is a list, arranged alphabetically, of all passenger cars manufactured. No attempt has been made to give the entire list in chart 1 as illustrated because space does not permit, and furthermore just a few 75 of the cars comprised in the complete list is thought to be sufficient for illustrative purposes.

In column 2 opposite each of the cars listed in column 3 there appears the number 80 designation of the cylinder head gasket used in the motor of that car, except in those instances where the motor is of the solid head type. In connection with the names of the cars listed in column 3, there also appears a 85 designation indicating the number of cylinders employed in the motors of said cars. For instance, the "Alsace" car has the number "4" after it, indicating a four cylinder motor, while the "Cleveland" is followed 90 by the number "6" indicating a six cylinder motor.

The next or third column, 4, of chart 1 is headed by the word "Model" to indicate the model designations adopted by the manufacturers of the cars listed in column 3. In column 4 there appears the number "44" opposite the "Abbott" car in column 3, thus indicating that said car is designated by its manufacturer as "Model 44." The "Champion" is indicated by a designation stating that it is of the "Tourist 40." Where the maker of a car has put out a number of different models of the same car, that also appears in column 4 after the particular cars 105 listed in column 3. Thus, a number of models of the "Crow-Elkhart" have been placed on the market from time to time, and, as shown in column 4, are known as models "K", "C", "E", "L", etc. 110

The next column, 5, is headed by the word "Year," and then follow the years, when known, that the various cars listed in column 3 were put out by their makers. It will be observed that the "Alsace" car listed was put out between 1920-21, while the first listed "Birch" car was put out between 1920-22, and the several models of the "Crow-Elkhart" were put out between 1917 and 1922.

10 The next column, 6, is headed by the word "Motor," and opposite the various cars listed on the chart there appear the names of the motors used in such cars. For instance, the motor used on the "Alsace 4," put out in 1920-21, is known as the "Lycoming" motor, Model "K." The Alsace car is an assembled car, and the motor is made by a motor manufacturer putting out a motor of the name mentioned. It will 15 also be observed that the first listed "Birch" car, put out in 1920-22, also uses a "Lycoming" motor, while the second "Birch" car, put out in 1918-22, having model designations "30 and 30-B," uses a "LeRoi" motor, 20 model "2 C." Down near the bottom of the list on chart 1 there is the "Studebaker 6" having a model designation of "Series 20-21" and put out in 1920-22. The motor used on this car is known as the "Studebaker" motor—that is, it is manufactured by the maker of the car and not bought from a motor manufacturer as is the case of several of the other cars listed in said chart.

25 As shown in Fig. 1, column 3 also contains the names of the motors used on the various cars, especially when a number of the cars marketed use the same make of motor. For instance, the "LeRoi" and the "Lycoming" motors are used on a number of different cars, and at 3^a and 3^b the names of these motors appear in column 3.

The next column, 7, is headed by a suitable indication designating which chart or page, as the case may be, if the charts are all in 30 book or pamphlet form, illustrates the cylinder head gaskets used on the motors of the cars listed in column 3. In chart 1, the heading of this column 9 is by the word "Page," and under it are the numbers referring to various charts or pages illustrating the various cylinder head gaskets mentioned in the first column 2 and used in the motors listed in connection with the passenger cars on chart 1. Before describing this 35 feature of my invention, I will refer to the next chart, 8, shown in Fig. 2.

Chart 8 contains a list of that class of motor vehicles different from the class covered by chart 1. The class covered by chart 40 8 is motor trucks and the word "Trucks" heads the chart as shown. Chart 8 is also divided into six vertical columns like chart 1. The first column 9 contains information similar to column 2 of chart 1, as applied to 45 trucks. The next column 10 is headed by

the word "Truck" and under it appear, in alphabetical arrangement, the names of all motor trucks manufactured and is similar to column 3 of chart 1, only trucks are listed instead of passenger cars as in chart 1. 70

The next column, 11, is headed by the word "Model" and under that appear the model designations used by the manufacturer for the trucks listed in column 10, following the same arrangement employed for 75 passenger cars in chart 1. The next column, 12, contains data with respect to the capacity of the various trucks listed in column 10. It will be observed that the first Acme truck listed is of the "5 ton" type, 80 while the second Acme truck listed is of the "2 ton" type. The "A M C" truck listed is of the "4 and 1 $\frac{1}{2}$ ton" type, and so on throughout the entire listing in the chart. Columns 13 and 14 are headed, respectively, 85 by the words "Motor" and "Page" and contain data similar to columns 6 and 7 of chart 1 only applied to the trucks listed in the chart.

Chart 15 shown in Fig. 3 contains a classification of those motor vehicles which are not included in the two classes covered by charts 1 and 8. The class of motor vehicles covered by chart 15 is shown as "Tractors" and that word heads the chart, as shown. Chart 90 15 is also divided into six vertical columns, like in the other charts described and containing similar data as applied to tractors. Column 16 gives the cylinder head gaskets by their number designation; column 17 is 100 headed "Tractor" and contains an alphabetical list of all tractors manufactured; column 18 is headed "Model;" column 20 is headed "Motor" and gives the names of the motors used on the tractors listed; and 105 column 21 is headed "Page" like the last column in each of the two charts previously described.

Column 19 is new with chart 15. It is headed "Rating" and contains information 110 with reference to the amount of horse power at the draw-bar and belt, respectively, of the tractors listed in the chart.

The next chart 22 is shown in Fig. 4, and this covers that class of devices and mechanisms which employ internal combustion engines and which classification is not covered by any of the classes in any of the other charts. The classification covered by chart 115 22 is of the miscellaneous kind and that word heads the chart, as shown. Under that title there is a suitable designation of the general type of devices that comprise the miscellaneous class, and such, it will be observed, includes "Farm lights," "Stationary 120 engines," etc.

Chart 22 is also divided into six vertical columns, 23 to 28, like in the previous charts and giving data particularly applicable to the devices covered by this miscellaneous 130

class. These columns are headed "McCord No.," "Miscellaneous," "Model," "Rating," "Motor," and "Page," respectively, and under them are listed the appropriate data following the same arrangement as in the previously described charts.

The "Miscellaneous" column 24 contains a list of names of all devices included in the miscellaneous classification, such as the 10 "Clark tructractor," "Delco light," "Gifford ice cutter," and so on throughout the list. The "Clark tructractor" is an industrial tractor on wheels, and is used about factories, yards, and other places, for hauling, etc.

15 The next chart for consideration is the one shown in Fig. 5 and is indicated by 29. This contains a picture of a cylinder head gasket, and that is indicated by 30. Associated with this picture is the numerical 20 designation given by the manufacturer of the gasket to the same, and in the chart the designation is "McCord No. 27," as shown. Chart 29 contains, in association with the 25 picture of gasket "No. 27," the name of the motor in which that gasket is used and also the names of all of the passenger cars, trucks, and tractors using that motor.

To set forth this information clearly, chart 30 29 is divided into, say, three columns 31 to 33. Heading the first column 31 is the name of the motor, to wit, "Lycoming," in which gasket No. 27 is used, and this is followed by the number "4" indicating the motor is of the four cylinder type. The next column 35 32 is headed by the word "Model" followed by the model designations of the motor in question. The last column 33 is headed by figures indicating the bore and stroke of said motor.

40 The first column 31 contains an alphabetical listing, by name, of all passenger cars and trucks using the motor designated at the head of the column. This list is divided into two groups or sections, one for 45 passenger cars and so headed, as at 31^a, and the other for trucks and so headed, as at 31^b. The next column 32 gives information with respect to the model designations of the motor vehicles listed in the first column.

50 The last column 33 is divided into two groups or sections, one for the passenger cars being headed by the word "Year" as at 33^a, and the other for trucks being headed by the word "Capacity" as at 33^b. Under 55 these respective headings appears the appropriate data, as shown in Fig. 5.

Chart 34 in Fig. 6 is in effect a continuation of chart 29 in Fig. 5, in so far as the upper portion thereof is concerned. This 60 has reference to the cylinder head gasket "No. 27" illustrated in chart 29 and covers the class of "Tractors," that is, those tractors using a Lycoming motor and in which a cylinder head gasket "No. 27" is employed. The data on this chart 34 is divided

into three columns which form a continuation of the columns 31 to 33 of chart 29, and are so indicated. The first column 31 is headed by the word "Tractor," the next column 32 by the word "Model," and the 70 third column 33 by "Rating." Under these headings appears the appropriate information, as shown.

Beneath this appears a specification of all gaskets, including the cylinder head gasket, 75 used in or about the Lycoming motor covered by charts 29 and 34. This data is divided into, say, seven vertical columns 35 to 41, headed as shown in Fig. 6. The first column 35 gives the gasket numbers; the second 80 column 36, the part numbers as adopted by the motor manufacturer for the gaskets designated in column 35. Column 37 gives the size of the gaskets designated and column 38, the type. Column 39 gives the name of 85 the gaskets, that is, for what purpose they are used; and column 40 gives the number of such gaskets used in or about a single motor. The last column 41 is the list price of such gaskets. 90

Below the data just mentioned, there appear on chart 34 pictures of three gaskets. The one 42 is a cylinder head gasket designated as "McCord No. 28," and the other two, 43 and 44, as "No. 1021" and "No. 95 1022," respectively. This gasket "No. 28" is designed for a motor used only on a special device, as a Fordson tractor and known as a "Fordson motor." The name of this motor appears beneath the gasket 100 illustration and also in connection with this appear the bore and stroke of such motor, as at 45. Below the name of the motor appears the name of the device on which it is used and the rating of that device, as shown. 105

In association with the data mentioned, the chart also contains data giving the gasket equipment for that motor in somewhat the same manner as in columns 35 to 41 above. It will be noted that gaskets Nos. 110 1021 and 1022, illustrated, appear at 31^a and 31^b, respectively, in the specification by being included in the first column by their number designations.

Chart 46 in Fig. 7 illustrates at 47 another 115 cylinder head gasket, designated as "No. 29." Below this the chart is divided vertically into three columns 48 to 50, headed, respectively, by the name of the motor using this particular gasket, the model of the 120 motor, and its bore and stroke, like chart 29 heretofore described. As in that chart, the first column 48 lists all passenger cars, trucks, and other devices using said gasket "No. 29." In column 49 appear the models 125 of the cars, etc., listed in column 48, and in column 50 appear, respectively, the years the passenger cars were put out and the capacity of the trucks listed. This chart may also picture a special gasket as at 51. 130

Fig. 8 shows another chart 52 carrying an illustration of a gasket 53 of a type used at the exhaust manifold. This chart is divided vertically into a number of columns 54 to 59 inclusive. The first column 54 headed "McCord No." contains a list of gaskets of the kind illustrated by the number designations. Column 55 gives the diameter of the center holes of the gaskets listed, while column 56 gives the diameters of the bolt holes in said gaskets. Column 57 gives the dimensions from center to center of the bolt holes and column 58 gives the overall dimensions. The last column 59, as its heading indicates, gives a list price.

It is preferable, although not essential, that all charts made in accordance with my invention be bound or otherwise connected together in pamphlet or other compact form for ready and convenient reference. When so connected they will be paged as suggested in the drawings.

One manner of use of the charts is as follows. The complete set of charts, bound together and paged, is supplied to a garage or repair station by the gasket manufacturer using the charts. A car is driven into the garage for repair. It is found that a new cylinder head gasket is required. The repair man first ascertains the name of the car, if he does not know the exact cylinder head gasket used. Say the car is an "Alsace 4." He refers to his charts and turns first to the alphabetical index of cars. He finds this car on chart 1 in column 3. He notes in column 2 that a "No. 29" gasket is required. He then goes to his stock and gets a No. 29 gasket.

Suppose that the repair man could not learn the name of the car, either because the driver did not know it or because there was no name appearing on the car, and he did not know its name by its general outside appearance. He would then find out the name of the motor used in the car. He finds this to be a Lycoming motor, model "K." He then refers to his alphabetical lists under passenger cars and looks for "Lycoming." He finds this at 3^b in column 3 of chart 1, and notes in column 2 that it uses a gasket No. 27.

Another illustration—suppose the car is a Birch. He does not know the name of the motor nor the model of the car. He finds out that the car was put out between 1918 and 1922 and that is all the information he has. He refers to the alphabetical lists of passenger cars and looks for the Birch car. He finds two listed as shown in chart 1. He looks in column 5 for the year data and by that traces the gasket number in column 2. In case he does not learn the name of the car or the name of the motor, nor can he find the gasket number on the old gasket, he looks through the charts at the gasket illus-

trations and in that way determines what gasket is needed.

Another use of the charts is made by the jobber or dealer as well as the repair man. Cylinder head gaskets, while similar in general appearance as to outline, are not alike. The jobber could not well afford and in fact would not put in stock a number of cylinder head gaskets for all makes of cars. If he did he would have duplicate stocks because some cars use the same type of motor. By referring to a chart containing an illustration of a cylinder head gasket, he finds listed all cars, trucks and the like using that gasket. Thus, he can put in stock the required quantity of certain gaskets and be able to supply such gaskets to all cars using the same by referring to the charts showing such gaskets. For instance, he stocks up on gaskets Nos. 27, 28, and 29, shown in charts 29, 34, and 46, and from those charts can readily ascertain the various cars and devices using such gaskets.

Another use of the charts is made in the following manner. A gasket other than a cylinder head gasket needs replacement. Say it is a gasket for the exhaust manifold and the gasket number is not shown. By measuring the old gasket, it can be identified by its part number by comparing its measurements with chart 52.

By referring to the gasket specifications in connection with the several motors, the number of gaskets and kinds used in and about a single motor may be readily and quickly ascertained, as disclosed, for instance, in chart 34.

In case there is no information at hand with respect to the name of the device, the model, the name of the motor, and the like, identification of the gasket may still be found by ascertaining the bore and stroke of the motor. While, in the illustration above with respect to the uses of my invention, I have referred in specific instances to 105 passenger cars, it is of course to be understood that the use of the charts with respect to trucks, tractors, etc., would be in the same manner. These charts give the jobber, dealer, repair man, and the like all information needed to readily and quickly identify the gaskets, and thus aid materially in merchandising the parts. They increase the service to the consumer by enabling the proper gaskets to be quickly ascertained and eliminate all trouble and delay as heretofore. Other advantages incident to my invention will be apparent to those having dealings with the products covered thereby.

As heretofore stated, solid head motors 125 do not use cylinder head gaskets, but other types of gaskets are employed in and about the same. To include such motors within the charts of my invention, I employ a chart or charts giving the kinds and numbers of 130

such gaskets, and have illustrated in Fig. 9 a portion of one of such charts and indicated the same by 60. This chart has appropriate heading indicating the fact that it lists all of the different kinds of gaskets employed in connection with a solid head motor. Beneath the heading there appears at 61 the name of a solid head motor which, as shown in chart 60, is a Buick motor of 10 the six cylinder type. Opposite that is the model of the motor, as at 62, and at 63 appears the bore and stroke. Beneath the name of the motor appears the classification of the car on which it is used and, as shown, it 15 is a passenger car, and under such designation appear the names of all cars using said motor. Under the title "Model" at 62 appear the models of all cars named in column 61, and in the last column appear the 20 years that such cars were placed on the market, following the same general arrangement as in the previous charts. The chart is then divided into a number of vertical columns 64 to 70, inclusive, having titles 25 "McCord No.," "Part No.," "Size," "Type," "Name of gasket," "Used per motor," and "List price," respectively, like in chart 34 in Fig. 6. In these columns appear appropriate data with respect to the different gaskets 30 used in connection with a solid head motor of the type covered by the chart, and in the first column 64 there are listed the gasket numbers or designations adopted by the gasket manufacturer to indicate the various 35 gaskets specified, as shown. This chart 60 is preferably bound in a compact or pamphlet form together with the other charts previously described, and has a suitable page designation, as indicated. It is to be understood of course that other charts like the one 40 will be employed for all of the various solid head motors in use, and the same character of data as appearing on the chart 60 will be employed in connection with the 45 other charts covering other solid head motors. By reason of a chart or charts applicable to solid head motors, the jobber, dealer, repair or garage man will also have at hand information with respect to the various gaskets 50 used in and about solid head motors, and the various gaskets may be readily and easily identified by referring to the charts in question.

While I have shown my invention applied 55 to gaskets for motors on motor vehicles, etc., it is of course to be understood that my invention could be used for merchandising other manufactured parts, and I do not wish to be limited in the application of my invention to any particular character of parts.

I claim as my invention:

1. A chart containing the symbols adopted to indicate the different parts made by one manufacturer for use in devices as 60 marketed by others, and the names of the

various devices in which said parts are used, the names of said devices being associated with said symbols in a manner permitting the parts used in said devices to be readily identified by referring to the names of said 70 devices.

2. A chart containing the symbols adopted to indicate the different parts made by one manufacturer for use in devices as marketed by others, and the names of 75 the various devices in which said parts are used, the names of said devices being associated with said symbols in a manner permitting the parts used in said devices to be readily identified by referring to the names 80 of said devices, where like parts are used in a number of said devices that fact appearing by having the symbols indicative of said parts associated with the names of such devices.

3. A chart containing the symbols adopted to indicate the different parts made by one manufacturer for use in devices as marketed by others, and the names of the various devices in which said parts are used, the 90 names of said devices being arranged in groups according to the classification of said devices and alphabetically in each group and associated with said symbols in a manner permitting the parts used in the devices in each group to be readily identified by referring to the names of said devices.

4. A plurality of charts, certain of said charts containing illustrations of the different parts made by one manufacturer for use in devices as marketed by others, and the other of said charts containing the symbols adopted to indicate said parts and the names 100 of the various devices in which said parts are used as well as references to said first mentioned charts, the names of said devices being associated with said symbols and references in a manner permitting a ready reference to be made to the parts used in said devices and to the charts containing the illustrations of said parts by referring to the names of said devices.

5. A plurality of charts, certain of said charts containing illustrations of the different parts made by one manufacturer for use in various devices as marketed by others, and the other of said charts containing the symbols adopted to indicate said parts and names of said devices as well as references 110 to said first mentioned charts, the names of said devices being associated with said symbols and references in a manner permitting a ready reference to be made to the parts used in said devices and to the charts containing the illustrations of said parts by referring to the names of said devices.

130

6. A chart containing a plurality of lists, one list containing the names of motor vehicles, another list containing the part numbers of the cylinder head gaskets used in 5 the motors of said vehicles, another list containing the names of the motors used in said vehicles, and another list containing certain information indicative of said vehicles other than their names and the 10 motors used therein, the data in said lists being so associated with each other that a ready identification may be had of the cylinder head gaskets used in said vehicles by referring to one or more of the other of 15 said lists.
7. A chart containing an illustration of a part made by one manufacturer for use in a mechanism made by another and employed in various devices marketed by 20 others, and the names of all of the devices in which said part is used, said names being arranged in groups according to the classification of said devices and alphabetically in each group.
- 25 8. A chart containing illustrations of a number of gaskets made by one manufacturer for use in connection with a motor made by another, one of the illustrations being of a cylinder head gasket for said motor, the name of said motor being associated with the part number of the cylinder head gasket, and a specification of all of 30 the other gaskets used in connection with said motor and including the part numbers 35 of the other of said illustrated gaskets.
9. A chart comprising a list of part numbers of different cylinder head gaskets as made by one manufacturer, a list of names of all motor vehicles using said gaskets, a 40 list of the models of said vehicles, a list of the years they were placed on the market, and a list of the names of the motors used therein, the data included in said lists being arranged opposite each other so that the 45 cylinder head gaskets may be readily identified by referring to one or more of said lists.
10. A chart containing several lists, one 50 list being of the part numbers of the different cylinder head gaskets made by one manufacturer, another list giving the names of all motor vehicles using said gaskets, said names being alphabetically arranged, another list giving the models of said vehicles, another list giving the names of the 55 motors used in said vehicles, and another list giving the rating of said vehicles, the data in said lists being so arranged with respect to each other that the gaskets used 60 in said vehicles may be readily identified by referring to one or more of said lists.
11. A plurality of charts, certain of said charts containing illustrations of the different cylinder head gaskets made by one 65 manufacturer for use in the motors of motor vehicles marketed by others, and the other of said charts containing the part numbers of said gaskets, the names of said vehicles, the names of the motors used therein, and other data as an aid to identifying 70 said vehicles, as well as reference to said first mentioned charts, said vehicle names being divided into groups in accordance with the classification thereof and alphabetically in each group.
- 75 12. A chart containing the part number of a cylinder head gasket used in one motor, the name of said motor, and the names of all devices using said motor.
13. A chart containing the part number 80 of a cylinder head gasket used in one motor, the name of said motor, the names of all devices using said motor, and a specification of all of the other gaskets used in connection with said motor and the total 85 number of each of said gaskets, the latter being identified by their part numbers.
14. A chart comprising the part numbers 90 of different cylinder head gaskets as made by one manufacturer, the names of all devices containing motors using said gaskets, the models of said devices, and other information with respect to said devices as an aid to identifying said gaskets; where any 95 of said devices have motors not using cylinder head gaskets that fact appearing in connection with said devices.
15. A chart containing the part numbers 100 of all of the various gaskets made by one manufacturer and used in and about a solid head motor, the name of the solid head motor, and names of all devices on which said motor is used.
16. A chart containing the part numbers 105 of the various gaskets made by one manufacturer and used in and about a solid head motor, the name of said motor, its model and bore and stroke, the names of all devices using said motor and other information with respect to said devices as an aid in identifying them, and information with respect to the various gaskets to identify the same by size, type, name, and whatever designation 110 is given to said gaskets by the manufacturer of the motor.
- 115 17. A chart containing an illustration of a part made by one manufacturer for use in a mechanism made by another, and the name of at least one of the mechanisms using said part.
18. A chart containing an illustration of a part made by one manufacturer for use in a mechanism made by another, and the name of at least one of the mechanisms using said part, together with a specification of other 120 allied parts used in connection with said mechanism.
- 125 19. A chart containing an illustration of a cylinder head gasket made by one manufacturer for use in a motor made by another,

- and the name of at least one of the motors using said gasket, together with a specification of the various other gaskets used in connection with said motor, the specification 5 identifying the gaskets covered thereby by size, type, name or where used, number used per motor, and part numbers adopted for said gaskets both by the maker of the motor and by the manufacturer of the cylinder 10 head gasket.
20. A chart containing an illustration of a cylinder head gasket made by one manufacturer for use in a motor made by another, the name of said motor, together with its 15 model, stroke and bore, and the name of at least one motor vehicle using said motor.
21. A chart containing an illustration of a cylinder head gasket made by one manufacturer for use in a motor made by another, the 20 symbol adopted by the manufacturer of said gasket to identify the same and being associated therewith, the name of said motor, the model thereof, its stroke and bore, and the name of at least one motor vehicle using said 25 motor, together with a specification of the various other gaskets used in connection with said motor, said specification identifying the gaskets covered thereby by size, type, number used per motor, name, and part numbers adopted therefor both by the maker of 30 the cylinder head gasket and of said motor.
22. A chart containing an illustration of a cylinder head gasket made by one manufacturer for use in a motor made by another, the 35 symbol adopted by the manufacturer of said gasket to indicate the same, the name of said motor, its model, and other information to readily identify it, and data giving the name of at least one motor vehicle using 40 said motor, said data giving the type of
- motor vehicle, whether a passenger car, truck or tractor, or the like, and the model or models thereof, together with the capacity of a truck and the rating of a tractor.
23. A chart containing the symbols adopted 45 to indicate the different cylinder head gaskets made by one manufacturer for use in motors made by others, and data giving the names and types of the various motor vehicles and other devices using said motors, together with the models of said vehicles and other devices, the years they were placed on the market, if passenger cars and trucks, their rating if tractors, and other information to identify said devices, said data being 50 arranged so that ready reference may be had for the cylinder head gaskets used in the motors of said devices.
24. A chart containing the symbols adopted 55 to indicate the different cylinder head and other gaskets made by one manufacturer for use in and about motors made by others, and data giving the names and types of the various motor vehicles and other devices using said motors, together with the models 60 of said vehicles and other devices, the years they were placed on the market, if passenger cars and trucks, their rating if tractors, and other information to identify said devices, said data being arranged so that 65 ready reference may be had for the cylinder head gaskets used in the motors of said devices, said chart containing illustrations of certain of said gaskets and identified where illustrated by the adopted symbols therefor. 70
- In testimony that I claim the foregoing as my invention, I affix my signature this 1st day of March, A. D. 1922. 75

MALCOLM McCORMICK.
